ORE WASHER

Marmaduke J. Lacy, Jr., Mount Pleasant, Tenn.

Application July 27, 1932, Serial No. 625,121

6 Claims. (Cl. 209—463)

My invention relates to certain new and useful improvements in machines for washing ores containing clay, chips, silt and other contaminating matter to be separated from the valuable constituents, such ores as phosphates, manganese, iron, and the washing of concrete aggregates.

One of the objects of the invention is to provide a simple, inexpensive, ruggedly constructed machine for the purpose stated which will make less slimes in washing the ore than is usual in machines of this character.

Another object is to provide a machine which will make a cleaner product than can be produced by machines now in use.

Again it is an object to provide a machine which will cause less breakage of soft ores such as phosphate ores.

Further, it is an object to provide a machine which requires less power to operate, will involve less expense for repairs when repairs become necessary, and which can be built for any capacity and in any sizes desired.

Further, the invention has for an object to provide an ore washer which is more flexible as to control of capacity and grade of product than other machines now known, and one which will deliver a better dehydrated product, clean of clay, slime, silt and chips than is possible with machines now known.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:

Figure 1 is a plan view of my machine.

Figure 2 is a vertical longitudinal section thereof on substantially the line 2—2 of Figure 1.

Figure 3 is a transverse section on the line 3—3 of Figure 2.

Figure 4 is a detail perspective view of one of the plow link units.

In the drawings in which like numerals of reference designate like parts in all of the figures, 1 represents the bottom longitudinal beams which incline upwardly toward the exit end of the machine, and 2 indicates the bottom longitudinal beams which incline downwardly from the entrance end of the machine. These beams are supported on suitable vertical supporting cross frames 3, 4, 5, 6 and 7 respectively. A wooden

bottom 8—9 is mounted on the beams 1 and 2 and wooden side walls 10 are provided, thus forming an elongated trough. This trough is provided with a metal lining 11.

Horizontal longitudinal top beams 45 are mounted on the frames 3 and 7 and carry drive shaft bearings 12 in which the driving shaft 13 is journaled, this shaft being preferably located adjacent to the outlet throat 42 of the trough. A set of spaced driving sprockets 14 are mounted on the shaft 13, over which sprockets the endless chains 25 pass. Adjacent the inlet end of the machine there is an upper idler wheel shaft 15 journaled in shaft carrying slide blocks 17 and carrying idler wheels 16, one for each chain. The slide blocks 17 are mounted in slotted guides 18 that are secured on the longitudinal beams 45, there being a take-up screw 19 with jam nut 20 provided for the purpose of moving the slides 17 to keep the chains taut.

The chains also pass over an idler drum wheel 21 carried by a shaft 22 journaled in suitable bearings within the trough adjacent to its point of lowest level.

23 is a chain drive roller shaft bearing block in which the shaft of an idler drum 24 is journaled, the drum being located about midway between the sprockets 14 and the idler wheel 16 so as to keep the upper flight of the chain substantially horizontal. The lower flight of chains from drum 21 to sprockets 14 runs parallel with the upwardly inclined bottom portion 9—11 of the trough for a purpose presently made clear.

Each chain 25 has provided at suitable intervals plow and drag bar links 26. Each of these links has a plow beam portion 27 carrying a plow share 28. It also has a drag bar flat 29 to which the cross bars or drag spacer bars 30 are secured in any suitable manner.

31 is a baffle located between the chain and the downwardly inclined bottom wall 8—11 of the trough so as to comprise a hopper-like entrance 41 into which the material is dumped.

32 is a water supply pipe from which several branches extend, the lowermost branch 33 being located below the water level adjacent to the drum 21 and is provided with spraying apertures 34 that are downwardly directed, there being a second branch 35 with downwardly directed spraying apertures 36 located in the trough below the water level but at a higher elevation than the branch 33. Both of the branches 33 and 35 are located above the lower flight of the chains.

37 is another branch pipe with spraying aper-

tures 38 directed downwardly by the pipe 37 and is located above the water level and above the lower flight of the chain. Beyond the range of the chains and adjacent to the outlet throat 42 is a fourth spray pipe 39 whose spraying apertures 40 are directed horizontally backward onto the material that is passed into the throat 42 from whence it is delivered by the discharge throat 43 supported on suitable beams 44.

10 Each branch pipe or duct 33, 35, 37, 39 has an individual control valve 46 so that the several spray pipes may be severally controlled.

15 A water overflow outlet 47 is provided in a side wall of trough so as to maintain a definite water line.

It is to be observed that the plow shares 28 have their lower edges in close proximity to the upwardly inclined bottom 9-11 of the trough in passing from the rollers 21 to the sprockets 14. 20 Furthermore, the plows on alternate chains are staggered with respect to each other so that as the plows are moved upwardly through the mass of aggregates in the bath the mass will be advanced up the incline and at the same time given 25 a lateral movement back and forth due to the staggered relation of the plows. The scraper bars 30 maintain a definite level of material on the up-going part of the machine and assist the plows in advancing the material from the pit of the trough beneath the rollers 21 to the outlet throat 42 above the water line.

30 The drag spacer bars 30 perform two functions, namely they hold the chains in alignment and prevent the plows from turning sidewise; they also act as skimmers for the top of the material and to drag the wash material to the discharge throat, thereby assisting in agitating the water and keeping the fine material in suspension to pass out through the overflow with the water to be recovered in other suitable machines for the purpose.

35 From the foregoing description, taken in connection with the accompanying drawings, it is thought the complete construction, operation and advantages of my invention will be clear to those skilled in the art to which it relates.

40 What I claim is:

1. In an ore washer and the like, a trough having an upwardly inclined bottom wall with a discharge throat at its highest portion and having a downwardly inclined bottom wall with an inlet at its highest portion, the two walls merging to form a pit in the trough, a plurality of endless chains mounted on wheels at both ends 50 of the trough and passed under an idler mounted in the trough at the pit, each chain having at intervals plow and cross bar links, each of which links having a plow beam carrying a plow share and also having a scraper cross bar flat, the plow carrying link of one chain being staggered with respect to those of adjacent chains, means to drive the chains in unison, and cross bars connecting the flats which are in transverse alignment, said trough having a water overflow 55 port to maintain a definite water line, and spray pipes in the trough for the purposes described.

60 2. In an ore washer and the like, a trough having an upwardly inclined bottom wall with a discharge throat at its highest portion and having a downwardly inclined bottom wall with an inlet at its highest portion, the two walls merging to form a pit in the trough, a plurality of endless chains mounted on wheels at both ends 65 of the trough and passed under an idler mounted in the trough at the pit, each chain having at

70 intervals plow and cross bar links, each of which links having a plow beam carrying a plow share and also having a scraper cross bar flat, the plow carrying link of one chain being staggered with respect to those of adjacent chains, means to drive the chains in unison, and cross bars connecting the flats which are in transverse alignment, said trough having a water overflow port to maintain a definite water line, spray pipes in the trough, said chains having flights extending parallel with the upwardly inclined bottom wall and flights extending horizontally from end to end along the top of the trough, and a chain carrying idler on the top of the trough.

75 3. In ore washers and the like, a trough having an entrance at one end and an outlet at the other end and provided with a water overflow below the level of said outlet, said trough having a

80 V-shaped bottom composed of a short wall at the inlet end and a long wall extending from the short wall to the outlet end of the trough, means to advance the aggregates from the lowermost part of the trough toward the outlet end and simultaneously impart to the same a lateral zig-zag movement, means for spraying water downwardly on the aggregates below the water line in the trough, other means for spraying water downwardly on the aggregates above the water level line in the trough, and further means to spray wash material as it passes the place of discharge.

85 40 said aggregate advancing and laterally moving means comprising a plurality of parallelly disposed endless chains each having at intervals plow links that have plow beams carrying plow shoes for longitudinally plowing through the aggregates in

90 the trough and moving the same laterally and forwardly, the plow of one chain being staggered with respect to those of adjacent chains, said links having cross bar flats and cross scraper bars extending transversely of the trough and connecting

95 those plow links which align transversely. 455

9. In ore washers and the like, a trough having an entrance at one end and an outlet at the other end and provided with a water overflow below the level of said outlet, said trough having a

100 V-shaped bottom composed of a short wall at the inlet end and a long wall extending from the short wall to the outlet end of the trough, means to advance the aggregates from the lowermost part of the trough toward the outlet end and simultaneously impart to the same a lateral zig-zag movement, means for spraying water downwardly on the aggregates below the water line in the trough, other means for spraying water downwardly on the aggregates above the water level line in the trough, and further means to spray wash material as it passes the place of discharge.

105 50 said aggregate advancing and laterally moving means comprising a plurality of parallelly disposed endless chains each having at intervals plow links that have plow beams carrying plow shoes for longitudinally plowing through the aggregates in the trough and moving the same laterally and forwardly, the plow of one chain being staggered with respect to those of adjacent chains, said links having cross bar flats and cross scraper bars extending transversely of the trough and connecting

110 those plow links which align transversely. 555

10. In ore washers and the like, a trough having an entrance at one end and an outlet at the other end and provided with a water overflow below the level of said outlet, said trough having a

115 V-shaped bottom composed of a short wall at the inlet end and a long wall extending from the short wall to the outlet end of the trough, means to advance the aggregates from the lowermost part of the trough toward the outlet end and simultaneously impart to the same a lateral zig-zag movement, means for spraying water downwardly on the aggregates below the water line in the trough, other means for spraying water downwardly on the aggregates above the water level line in the trough, and further means to spray wash material as it passes the place of discharge.

120 60 said aggregate advancing and laterally moving means comprising a plurality of parallelly disposed endless chains each having at intervals plow links that have plow beams carrying plow shoes for longitudinally plowing through the aggregates in the trough and moving the same laterally and forwardly, the plow of one chain being staggered with respect to those of adjacent chains, said links having cross bar flats and cross scraper bars extending transversely of the trough and connecting

125 those plow links which align transversely, and means to maintain said chains taut, and a shaft with a drum mounted on top of the trough above the water level over which said chains pass.

130 70 65 75 80 85 90 95 100 105 110 115 120 125 130 135 140 145 150

13. In ore washers and the like, a trough having an entrance at one end and an outlet at the other end and provided with a water overflow be-

low the level of said outlet, said trough having a V-shaped bottom composed of a short wall at the inlet end and a long wall extending from the short wall to the outlet end of the trough, means to advance the aggregates from the lowermost part of the trough toward the outlet end and simultaneously impart to the same a lateral zig-zag movement, means for spraying water downwardly on the aggregates below the water line in the trough, other means for spraying water downwardly on the aggregates above the water level line in the trough, further means to spray wash material as it passes the place of discharge, said aggregate advancing and laterally moving means comprising a plurality of parallelly disposed endless chains each having at intervals plow links that have plow beams carrying plow shoes for longitudinally plowing through the aggregates in the trough and moving the same laterally and forwardly, the plow of one chain being staggered with respect to those of adjacent chains, said links having cross bar flats and cross scraper bars extending transversely of the trough and connecting those plow links which align transversely, means to maintain said chains taut, and a shaft with a drum mounted on top of the

trough above the water level over which said chains pass, said trough being metal-lined and said plows being disposed to travel with their bottoms in close proximity to the lining on the upwardly inclined bottom wall of the trough.

80

6. In a washer for ore and aggregates, a trough of triangular shape in vertical longitudinal section open at the top and having a bottom provided with a short steep entrant portion and a long gradually inclined outgoing portion, an endless conveyor composed of parallel chains mounted on rotating supports, two of which supports are located on the trough above the water line and one of which is submerged below the water line and located adjacent the angle at the bottom of the trough made by the juncture of the entrant and outgoing portions thereof, said chains each having a portion paralleling said outgoing portion of the trough bottom, plows rigidly secured to said chains, said chains each comprising plow links and connecting links between the plow links, the plows of one chain being staggered with respect to the plows of an adjacent chain, and cross bars connecting alternate chains together at the rear of the plows for the purposes described.
